CLAIM

The ornamental design for a bottle closure, as shown and described.

DESCRIPTION

FIG. 1 is a front view of a bottle closure showing our new design, the rear view being a mirror image thereof; FIG. 2 is a top view of a bottle closure depicted in FIG. 1; FIG. 3 is a bottom view of the bottle closure depicted in FIG. 1; and,

FIG. 4 is a side view of the bottle closure depicted in FIG. 1 representing a partial rotation of the bottle closure about its vertical center axis from the front view depicted in FIG. 1, the opposite side view being a mirror image thereof.
